UNITED STATES PATENT OFFICE.

MOSES F. CARR, OF NEWTON, MASSACHUSETTS, ASSIGNOR TO CARR FASTENER COMPANY, OF CAMBRIDGE, MASSACHUSETTS, A CORPORATION OF MAINE.

SEPARABLE FASTENER.

1,387,126.

Specification of Letters Patent.

Patented Aug. 9, 1921.

Application filed January 24, 1920. Serial No. 353,758.

To all whom it may concern:

Be it known that I, MOSES F. CARR, a citizen of the United States, and resident of Newton, in the county of Middlesex and

5 Commonwealth of Massachusetts, have invented an Improvement in Separable Fasteners, of which the following description, in connection with the accompanying drawings, is a specification, like characters on 10 the drawings representing like parts.

This invention pertains to improvements in separable fasteners and methods of securing parts of the same to their carrying fabric. It is among the objects of the invention to provide a simple and effective securing of the socket of stud and socket fasteners to a carrying fabric, preferably without perforation of the fabric.

In the drawings, which show a preferred 20 construction of one illustrative embodiment of my invention:

Figure 1 is an elevation of two pieces of fabric held together by a preferred form of fastening;

25 Fig. 2 is a section on the line 2—2 of Fig. 1;

Fig. 3 illustrates two pieces of fabric held together by a plurality of such fastenings;

Fig. 4 is a plan view of a preferred form 30 of socket prior to the securing thereof to its carrying fabric;

Fig. 5 illustrates diagrammatically the preferred form of socket, the fabric to which it is to be secured and the preferred form 35 of socket-securing means, preferably a cap, together with illustrative forms of suitable sets which may be used to press the parts together to secure them to the fabric;

Fig. 6 is a plan view of a preferred form 40 of stud; and

Fig. 7 is a side elevation of the stud, showing the same in its diagrammatic relation to the fabric and stud-securing means prior to assembly thereof in interlocked relationship 45 shown in Fig. 2.

Referring to the drawings and to the preferred form of my invention selected for illustrative purposes, I have shown a fastener including a stud 8 of the general type 50 shown in the co-pending application of Fred S. Carr, Serial No. 351,780, filed January 16th, 1920, adapted to be secured to its carrying fabric 9 by having its base expanded within a stud-securing part 10 located on the 55 opposite side of the stud carrying fabric 9

from the stud, the stud serving to press the fabric within the stud-securing part 10 and interlock these parts with the fabric between them.

I have also shown a socket 12, which preferably carries a spring 13, which may be secured therein by suitable indented bosses 14, the socket preferably having a stud-receiving aperture 15, which may be notched at opposite ends to provide an interlock against 60 separation by lateral strain, and having expansible projections 16, which may be formed by a continuation of the flange 17 of the socket, the expansible continuation of the socket rim preferably being slotted to 65 facilitate expansion, as hereinafter more fully described.

Cooperating with the socket, I may provide socket-securing means providing a means, herein shown as the lip 18, adapted to 75 cooperate with the expansible or distortable part 16 of the socket to grip the socket-carrying fabric 19 therebetween. To prevent relative displacement of the parts 16 and 18 in the general direction of the plane 80 of the fabric 19, I preferably include on the socket-securing means a part 20 adapted to overlie the expanded projections 16 of the socket, and to provide for expansion of the parts 16, I may provide anvil means 21 on 85 the socket-securing parts. The parts 18, 20 and 21 may conveniently be formed as an integral ring, which may be called a cap, especially where the center portion 22 thereof is filled in by the sheet of metal which 90 forms the parts 18, 20 and 21.

To attach the socket to its carrying fabric, the parts may be assembled in the position shown in Fig. 5, the socket 12 being located on one side of the socket-carrying fabric 95 19 and the socket-securing means being located on the other side of the fabric. If, now, the socket is pressed against the socket-securing part, the fabric 19 therebetween, the expansible projections from the socket 100 will be deflected outwardly by the anvil portion 21 of the socket-securing means until an interlock with the parts 18 of the socket-securing element is effected. This expansion or distortion of the interlocking parts will 105 be effected while the fabric lies between the part to be expanded or distorted and the anvil part which effects the distortion. Where the co-operating parts are formed of relatively light sheet brass or other similar 110

material, it will be found advantageous to provide dies adapted to be pressed one toward the other to effect the securing together of the parts, the dies preferably fitting the parts relatively closely to back-support the same and prevent undesired crushing of the parts which might in some instances arise if the setting force were unevenly applied.

10 It will be understood that I use the word "fabric" in its broader sense to include not only woven materials, but any flexible carrying medium.

While I have shown and described a preferred form of one embodiment of my invention and a preferred method of practising the same, it will be understood that changes involving omission, substitution, alteration and reversal of parts, and even 20 changes in the mode of operation, may be made without departing from the scope of my invention, which is best defined in the following claims.

Claims:

25 1. A socket for separable fasteners comprising, in combination, a spring-containing element having an expansible part or parts and coöperating securing means for securing the spring-containing part to a 30 carrying fabric, said securing means located on the opposite side of the fabric from said spring-containing element and providing spreading means effective through the fabric for expanding said expansible part or parts, 35 said securing means also providing means coöperating with said expansible part or parts for gripping the fabric.

2. A metallic-secured socket for separable fasteners presenting, when assembled with 40 the socket-carrying fabric, a casing having an expansible part or parts, and a casing-securing part located on the opposite side of the fabric from said casing and providing spreading means effective through the fabric 45 for expanding said expansible part or parts, said securing means also providing means coöperating with said expansible part or parts for gripping the fabric.

3. A metallic-secured socket for separable fasteners presenting, when assembled with 50 the socket-carrying fabric, a dish-shaped casing having a stud-receiving aperture through the face thereof and a flaring rim, and a casing-securing part located on the opposite side of the fabric from said casing, 55 said securing part presenting a peripheral bead, the outer wall of which underlies said flaring rim and the inner wall of which overlies said flaring rim, the fabric interposed and pressed between said flaring rim and the 60 interior walls of said bead.

4. A socket for separable fasteners comprising but three parts,—a socket casing, a spring therein and a socket securing cap, said socket casing and cap located on opposite 65 sides of the socket-carrying fabric and securing the socket to the fabric by gripping the fabric between interlocking parts of the socket casing and cap.

5. A socket for separable fasteners comprising but three parts,—a socket casing, a spring therein and a socket-securing cap, said socket casing and cap located on opposite sides of the socket-carrying fabric and securing the socket to the fabric by gripping the fabric between interlocking parts of the 75 socket casing and cap while maintaining the fabric imperforate.

6. A metallic-secured socket for separable fasteners presenting, when assembled with 80 the socket-carrying fabric, a dish-shaped casing having a stud-receiving aperture through the face thereof and a flaring rim, and a casing-securing part located on the opposite side of the fabric from said casing, 85 said securing part presenting a peripheral bead, the outer wall of which underlies said flaring rim and the inner wall of which overlies said flaring rim, the fabric interposed and pressed between said flaring rim and the 90 interior walls of said bead and underlying a protecting central portion of said securing part.

In testimony whereof, I have signed my name to this specification.

MOSES F. CARR.
